E. E. NEAL

BAG FILLING DEVICE

Filed Feb. 11, 1921

by his atty. Charles T. Gooding.

UNITED STATES PATENT OFFICE.

ENOCH E. NEAL, OF MALDEN, MASSACHUSETTS.

BAG-FILLING DEVICE.

Application filed February 11, 1921. Serial No. 444,153.

To all whom it may concern:

Be it known that I, ENOCH E. NEAL, a citizen of the United States, residing at Malden, in the county of Middlesex and State 5 of Massachusetts, have invented new and useful Improvements in Bag-Filling Devices, of which the following is a specification.

This invention relates to a device for 10 filling bags.

The object of the invention is to provide a receptacle, preferably mounted upon wheels, from which coal may be transferred by gravity into canvas bags, said bags being 15 suspended by their handles from a support and held open in position to receive the coal from the delivery chute of the receptacle, the support yielding after a predetermined quantity of coal has been delivered into the 20 bag which is thereafter gradually lowered by the support as the weight of the coal within the bag increases until the bottom of said bag rests either upon the ground or upon a suitable platform provided therebelow 25 where the bag remains until completely filled, after which the handles thereof may be disengaged from the support without the necessity of lifting said bag therefrom by forcing the support downwardly 30 slightly and slipping the handles from said support, the entire bag filling operation being quickly consummated with a minimum amount of effort on the part of the operative.

35 The invention consists in the combination and arrangement of parts set forth in the following specification and particularly pointed out in the claims therof.

Referring to the drawings:

40 Figure 1 is a side elevation of a bag filling device embodying my invention, a portion thereof being broken away to save space in the drawings.

Fig. 2 is an enlarged sectional plan view 45 taken on the line 2—2 of Fig. 1.

Fig. 3 is a vertical section taken on the line 3—3, Fig. 2.

Like numerals refer to like parts throughout the several views of the drawings.

50 In the drawings, 5 represents a coal receptacle of any desired size and construction and preferably, though not necessarily, supported by an axle 6 upon wheels 7 and also by legs 8. The receptacle 5 is provided 55 with a sloping bottom 9 which is extended

at 10 through an opening 11 provided in the side wall of the receptacle to also constitute the bottom of a delivery chute 12. Fast to the receptacle 5 adjacent to the opening 11 are vertically disposed angle irons 13 to 60 which are secured plates 14 which constitute the sides of the delivery chute 12.

The passage of the coal from the receptacle 5 down the delivery chute 12 is controlled by a gate 15 which is pivoted upon a 65 horizontally disposed shaft 16 mounted in the angle irons 13. A latch 17 pivoted upon one of the side plates 14 is adapted to engage an angle iron 18 which forms a part of the gate 15 to prevent said gate from accidentally 70 being forced open when the receptacle 5 is being filled with coal. The gate 15 is raised and lowered manually by an operative who grasps a handle 19 provided upon the angle iron 18, or any other suitable position upon said gate. 75

A slide 20 constituting an auxiliary gate is also provided adapted to slide vertically upon the side wall of the receptacle 5 in front of the opening 11 being guided in vertical ways 21 adjacent to the angle irons 13. The slide 20 is provided for the purpose of regulating the volume of coal which may enter the delivery chute 12 through the opening 11, a relatively larger opening being 80 required when large sizes of coal are being handled than is required when small sizes are handled as the small sizes of coal flow more freely than the large. The slide 20 is securely held at any 85 desired height by a hasp 22 fast to the receptacle 5, said hasp being provided with a plurality of openings 23 therein through which a staple 24 fast to the slide 20 may project as illustrated in Figure 3, and thereby hold the slide 20 at the height required. 90

A bag 25 of the well known type used in delivering coal and preferably constructed of canvas or some other strong fabric is suspended by handles 26 beneath the end of 100 the delivery chute 12 from a support 27. The support 27 comprises a pair of arms 28 each of which is pivoted upon the axle 6 and has a laterally projecting curved plate 29 fast thereto constituting a handle rest 105 from which the bag 25 is suspended. Springs 30 extend between the arms 28 and the shaft 16 and act to always pull the outer ends of said arms upwardly to position the top of the bag 25 just beneath the end of 110

the delivery chute 12, the arms contacting with the lower edge of the side wall of the receptacle 5 which constitutes a stop therefor. There is sufficient tension upon the 5 springs 30 to allow a considerable amount of coal to be transferred from the receptacle into the bag 25 before said tension is overcome and the weight of the coal within the bag causes the support to descend and de- 10 posit the bag upon the ground, floor or a suitable platform located therebeneath. Side plates 31 are fastened to the inner sides of the outer portions of the arms 28 to guide the coal in its passage from the delivery 15 chute 12 into the bag 25 when said bag is in its lowered position. A circular band 32 is fastened to the side plates 31 and when the bag is suspended from the support 27, said band is located just inside the open end of 20 said bag and therefore acts to hold said bag open. Also fast to the side plates 31 is a bar 33 which is twisted to present a horizontally disposed flat surface positioned just above the band 32 to form a rest for the 25 knee of the operative when the handles 26 of the bag are disengaged from the handle rests 29. Angles 34 projecting downwardly from the receptacle 5 constitute stops to limit the downward movement of the 30 arms 28.

The general operation of my improved bag filling device is as follows:—An empty bag 25 is placed upon the support 27, the handles 26 of said bag passing over the handle rests 29. Coal within the receptacle 5 enters the delivery chute 12 through the opening 11, the amount of coal entering said chute being regulated by the auxiliary gate 20. The operative then raises the gate 15 and allows the coal to flow from the delivery chute 12 into the bag 25 which is held wide open by means of the circular band 32. The bag being suspended by its handles, the weight of the coal as it enters the bag opens out any creases or folds that may be formed therein and after a small amount of coal has entered the bag causes the sides thereof to hang perfectly taut. After a predetermined amount of coal has flowed into the bag, the quantity being determined by the tension of the springs 30 the weight of the coal will cause the outer end of the support 27 to descend until the bottom of the bag 25 rests either upon the ground, floor or upon 55 a low platform which may be located beneath the bag if it is so desired. The bag thereafter remains in this lowered position until the flow of coal is stopped by lowering the gate 15. The operative then places his 60 knee upon the rest 33 and forces the support 27 downwardly a sufficient amount to allow the handles 26 of the bag to be pushed laterally from the handle rests 29 which is accomplished without the necessity of lifting 65 the bag with the coal therein. When the

knee is again removed from the rest 33, the support 27 will immediately be drawn upward by the springs 30 to its original position. When the receptacle 5 is to be filled with coal, the latch 17 is moved from the full line position in Figure 1 to the dotted line position in said figure in which position it will prevent the gate 15 from being accidentally raised by the pressure of the coal as it enters the receptacle. 75

While it is preferable to have the receptacle 5 mounted upon wheels in order that the device may be moved from one location to another this is not necessary as it is evident that the receptacle 5 may have a large 80 capacity and be permanently located. It is also evident that grain, vegetables and other articles may be handled in place of coal if it is so desired, and it is evident that such articles may be fed into baskets or other suitable containers if they are provided with flexible handles capable of being attached to the support 27. 85

I claim:—

1. A bag filling device having, in combination, a receptacle, a delivery chute projecting therefrom, means to control the passage of material from said receptacle through said chute, a support pivotally mounted adjacent to said delivery chute and embodying therein a pair of oppositely disposed handle rests adapted to have a bag suspended therefrom by the handles thereof, means to yieldingly support the outer end of said support, means yielding downwardly in unison with said bag support to guide material from said delivery chute into said bag, means to hold the mouth of said bag open and means to limit the downward movement of said support. 95

2. A bag filling device having, in combination, a receptacle, a delivery chute projecting therefrom, a gate adapted to control the passage of material from said receptacle through said chute, an auxiliary gate to limit the volume of material entering said chute, a pair of arms, pivotally mounted beneath said delivery chute, a handle rest projecting from each of said arms respectively and adapted to have a bag suspended therefrom and springs adapted to yieldingly support the outer end of said arms. 100

3. A bag filling device having, in combination, a receptacle, a delivery chute projecting therefrom, a gate adapted to control the passage of material from said receptacle through said chute, an auxiliary gate to limit the volume of material entering said chute, a pair of arms pivotally mounted beneath said delivery chute, a handle rest fast to each of said arms respectively and adapted to have a bag suspended therefrom, springs adapted to yieldingly support the outer end of said arms and side 110 115 120 125 130

plates fast to the outer end of said arms adapted to guide said material from said delivery chute into said bag.

4. A bag filling device having, in combination, a receptacle, a delivery chute projecting therefrom, a gate adapted to control the passage of material from said receptacle through said chute, an auxiliary gate to limit the volume of material entering said chute, a pair of arms pivotally mounted beneath said delivery chute, a plate constituting a handle rest projecting laterally from each of said arms respectively and adapted to have a bag suspended therefrom, springs adapted to yieldingly support the outer end of said arms, side plates fast to the outer end of said arms adapted to guide said material from said delivery chute into said bag and a band fast to said side plates adapted to hold the mouth of said bag open.

5. A bag filling device having, in combination, a receptacle, a delivery chute projecting therefrom, a gate adapted to control the passage of material from said receptacle through said chute, an auxiliary gate to limit the volume of material entering said chute, a pair of arms pivotally mounted beneath said delivery chute and adapted to have a bag suspended therefrom, springs adapted to yieldingly support the outer end of said arms, side plates fast to said arms adapted to guide material from said delivery chute between said arms during the yielding movement thereof, a band

fast to said side plates adapted to hold the mouth of said bag open and a knee rest extending from said side plates above said band.

6. The combination with a chute of a pair of arms pivotally mounted upon an axis extending transversely of said chute and adapted to have a bag suspended therefrom, means adapted to yieldingly support the outer end of said arms, side plates fast to said arms adapted to guide material from said chute between said arms during the yielding movement thereof and means to tie the outer ends of said arms together and hold the mouth of said bag open.

7. The combination with a chute of a pair of arms pivotally mounted upon an axis extending transversely of said chute and adapted to have a bag suspended therefrom, means adapted to yieldingly support the outer end of said arms, side plates fast to said arms adapted to guide material from said chute between said arms during the yielding movement thereof, a band fast to said side plates adapted to hold the mouth of said bag open and a knee rest extending from said side plates above said band.

In testimony whereof I have hereunto set my hand in presence of two subscribing witnesses.
